Patented Mar. 11, 1969

213,501

CHRISTMAS TREE ORNAMENT

Dario Moranduzzo, Via Aretina 161, Florence, Italy

Filed Apr. 3, 1968, Ser. No. 11,291

Term of patent 3½ years

U.S. Cl. D29—1
Int. Cl. D11—05

I claim:

The ornamental design for a Christmas tree ornament, as shown.
